UNITED STATES PATENT OFFICE

REGINALD J. ALDEN, OF SPRINGFIELD, MASSACHUSETTS

CARTRIDGE

Application filed December 21, 1927. Serial No. 241,571.

This invention relates to small arms ammunition and more particularly to a cartridge having a projectile consisting of a semi-soft solid, or a liquid mass.

One object of the invention is to provide a small arms cartridge to be used in a short barrel gun, whereby a certain degree of accuracy in the travel of the projectile is imparted thereto by reason of the peculiar construction of the cartridge.

Another object is to provide a cartridge adapted to fire a projectile consisting of a semi-soft solid or a liquid mass and of such nature that a person hit with same will be temporarily disabled but not permanently injured.

Further objects will be apparent from the following description and accompanying drawings of my invention in which:

20 Fig. 1 is an end view of an empty cartridge embodying one of the features of my invention;

Fig. 2 is a cross sectional view taken on the line 2—2 of Fig. 1;

25 Fig. 3 is a longitudinal cross sectional view of a loaded cartridge embodying further features;

Fig. 4 is an end view of Fig. 3; and

Fig. 5 is a side view in elevation of my

30 cartridge.

In the drawings, 1 represents a cylindrical shell comprising the cartridge proper preferably made of suitable metal. The shell 1 is provided with the usual percussion cap or primer 2 at one end and packed adjacent thereto is the explosion charge 3 preferably consisting of quick burning powder or any other suitable explosive. The charge 3 is confined within the shell 1 adjacent the primer

35 2 by means of the usual wadding 4. Adjacent the wadding 4, I preferably insert the wadding 5 having a greater thickness at the periphery than at the center thereof or having

40 concave sides, as shown in Fig. 3, for a purpose which will be hereafter described. The projectile 6 is next inserted and confined within the shell by the wadding 7 which is

45 also preferably of a similar shape as the wadding 5. The inside of the shell is also pro-

50 vided with the rifling grooves 8 and lands 9

which extend inwardly from the discharge end of the shell preferably for a considerable distance as clearly shown in Fig. 2.

The projectile 6 is wholly confined within the shell between the waddings 5 and 7 and the wall of the shell and I also provide a space 10 by an extension of the enclosing shell wall for a considerable distance beyond the projectile. It will thus be seen that upon firing my improved cartridge from a short barrel gun wherein the cartridge occupies most of the barrel, the shell itself serves as a rifled barrel for the projectile whereby the desired accuracy for the flight of the projectile is obtained.

In the present embodiment of my invention, the projectile 6 consists of a liquid which upon impact against a person will temporarily disable that portion of the body hit but not permanently injure same. To this end, I have found that a gas such as sulphur dioxide liquefied by pressure is suitable although any other semi-solid, liquid, or liquefied gas having the same or similar results on a person may be used without departing from the scope of my invention.

70 In the use of liquefied sulphur dioxide as a projectile, which is normally a gas but which assumes a liquid form under a pressure of 30 lbs. or so to the square inch, the mass of liquid upon discharge from the cartridge will continue to remain in its liquid compact mass state for a considerable range of flight depending upon the force of the explosive charge. The liquid will thus arrive at its target as a slug so as to be capable of wounding any person hit. Upon impact, the mass scatters and spreads over a considerable portion adjacent the part hit whereby that portion of the body is temporarily disabled or 75 paralyzed due somewhat to the shock of the impact but more especially to the nature and character of the projectile. With a liquefied gas projectile such as sulphur dioxide, the action of the liquid gas in changing to a gaseous state practically freezes that portion of the body with which the liquid comes in contact and thereby numbs the same causing a temporary paralysis. In addition to this direct disabling effect of a liquefied gas, as a 80

projectile, the use of sulphur dioxide causes obnoxious fumes to be inhaled which still further incapacitates the person hit.

In employing a liquid gas as a projectile, the mass of liquid being under pressure must of necessity be hermetically confined and tightly sealed within the shell. In order to insure such a positive seal, I have utilized the pressure of the liquid gas itself by reason of the special shape of the waddings 5 and 7. It will be seen that the pressure within the liquid mass 6, being greater than that on the outer concave faces of the waddings 5 and 7, tends to force the waddings outwardly whereas by the outer concave portions of the waddings tend to spread the edges thereof against the shell and thus tightly seal the joint therebetween.

It is also desirable when using liquid as a projectile to minimize disturbing effects at its outer surface when ejected which might act to tear apart the mass from its slug formation. For this purpose, it is of advantage to make the extended portion of the containing shell function as the ordinary gun barrel and to provide the desired rifling grooves in the interior of said shell. In this way, the usual abrupt change of surface friction upon the projectile when the projectile leaves its shell and engages the ordinary barrel grooves is avoided. It will also be noted that the rifling grooves of the present improved shell are extended far enough toward the base so that the projectile is engaged by said grooves when it starts on its flight and does not have to find its engagement with the rifling grooves after leaving the shell as is the case with ordinary projectile and gun barrels. These features of improvement insure much less disturbance to my liquid projectile than would otherwise occur when it is fired.

Claims:

1. A cartridge comprising, a shell provided with a percussion cap and an explosive propelling charge, and a projectile comprising a compact mass of liquid wholly confined within said shell and adapted to be ejected in an unconfined state by said charge.

2. A cartridge comprising, a shell provided with a percussion cap and an explosive propelling charge, a projectile comprising a compact mass of liquid wholly confined within said shell and spaced from the discharge end of said shell, said projectile adapted to be ejected in an unconfined state by said charge.

3. A cartridge comprising, a shell provided with a percussion cap and an explosive charge, a projectile comprising a compact mass of liquefied sulphur dioxide wholly confined within said shell and being spaced from the discharge end of said shell, said projectile adapted to be ejected in an unconfined state by said charge.

4. In a cartridge comprising a shell pro-

vided with a percussion cap and an explosive propelling charge, a projectile comprising a compact mass of liquid under pressure wholly confined within said shell between masses of wadding having concave outer surfaces, said projectile being spaced from the discharge end of said shell and adapted to be ejected therefrom in an unconfined state.

5. A cartridge comprising a shell provided with a percussion cap and an explosive propelling charge, a projectile comprising a compact mass of liquefied sulphur dioxide wholly confined within said shell and being spaced from the discharge end of said shell, said projectile adapted to be ejected in an unconfined state by said charge, and rifling grooves on the inside of said shell.

6. In a cartridge comprising a shell provided with a percussion cap and an explosive propelling charge, a projectile comprising a compact mass of liquid under pressure wholly confined within said shell between masses of wadding having concave outer surfaces, said projectile being spaced from the discharge end of said shell and adapted to be ejected therefrom in an unconfined state, and rifling grooves on the inside of said shell and extending to the rear of said projectile for engagement therewith.

In testimony whereof I have affixed my signature.
